(57) **CLAIM**

The ornamental design for a keypad for door lock, as shown and described.

DESCRIPTION

FIG. 1 is a top, front, right side perspective view of a keypad for door lock;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dash-dash broken lines show portions of the keypad for door lock that form no part of the claimed design. The long-dash-short-dash broken lines represent boundaries of the claimed design and form no part of the claimed design. The dash-dash broken lines radiating from the bar shown in FIGS. 1, 2, 4, 5 and 6 represent illumination only and form no part of the claimed design.
